CONTROL COCK FOR GASEOUS FUEL
BURNERS BURNING A MIXTURE OF
TWO GASES

Harry T. Wilmarth, Attleboro, Mass.

Application April 9, 1946, Serial No. 660,732

6 Claims. (Cl. 158—27.4)

1

My invention relates to improvements in safety cocks or devices for gaseous fuel burners, particularly those of the type adapted to mix two gases in the burner prior to their ignition, one of which is inflammable and the other is not, but may be a supporter of combustion, although many features of my device may be employed in use with a burner burning a single gas only.

A main object of my invention is to provide a control unit which is operated by the actual burner itself thereby providing a substantially fool-proof device including a combination valve handle and hanger for the burner which will operate when the burner is hung when not in use to automatically shut off the gas supply or lower it to a small pilot flame only.

An object of my invention, therefore, is to provide a safety device against fire. Many fires have been caused in soldering and brazing plants where the gas burners have often been left burning full speed between jobs or have hung on the hooks provided therefor with a full flame, thereby increasing the fire hazard. Employing my invention, however, the flame is positively cut down to a small safe pilot flame when the burner is properly put away between the periods of its use.

A further object of my invention is to save the amount of gas employed, as the device is automatically shut off when the burner is placed in position on its holder and turned on automatically when the burner is lifted from its holder for use, and thus there is no loss in gas in burning it when it is not needed.

A further object of my invention is to provide a device which is always properly adjusted when ready for use, as placing the burner on its holder automatically either turns the burner off or reduces the flame to pilot size so that the correct proportion or mixture of gases is always present to give the proper flame when the burner is removed from its holder. In prior devices it has been necessary to separately shut off both gases and readjust the respective proportions thereof when the burner is relighted.

A further object of one embodiment of my invention is to provide a continuously burning pilot flame of the inflammable gas only which is of such a size as to be safe during its period of use and which will also permit the device to again be used without relighting the flame thereby additionally saving any gas which might be lost in relighting the burner as well as time saved in its readjustment.

A further feature of my invention relates to

2

the use thereof in burners which burn two gases mixed in the burner, one of said gases being inflammable like fuel gas, natural gas, acetylene, Philgas, etc., and the other being a non-inflammable supporter of combustion like compressed air, oxygen, etc. In order that the pilot flame may be continuously maintained, it is highly desirable that the inflammable gas reach the burner prior to the time that the non inflammable gas reaches it in sufficiently large amounts to blow out the pilot flame, and my invention specifically relates to a structure wherein the flow of inflammable gas is speeded up to insure that such a supply of inflammable gas will always be present so as to maintain the flame burning prior to and after the arrival of the non inflammable gas at the burning tip.

A further feature of my invention relates to the specific structure of means I preferably employ to automatically open my improved device with a free flow of gas when the burner is lifted off the handle.

Further features of my invention relate to improvements in structure of the component parts thereof, including the means I preferably employ to mount my device on a work table or other support.

These and such other objects of my invention as may hereinafter appear will be best understood from a description of an embodiment thereof of such as is shown in the accompanying drawings.

In the drawings, Fig. 1 is a diagrammatic perspective view showing my invention in use with a blow pipe burner of standard type for burning a mixture of two gases, one of which is inflammable having flexible pipes connecting said gases to the burner with my improved control cock interposed in said flexible pipes and with portions thereof broken away and shown in section to illustrate the structure thereof with the burner lifted away from its hanger hook to permit the control device to automatically move to a burning position in use.

Fig. 2 is a diagrammatic perspective view of the same parts shown in Fig. 1 with the burner hung on the hanger handle to move my control device to a shut off position permitting a slight leakage of inflammable gas therethrough to provide a pilot flame, with portions of my improved device also being partially broken away and shown in section.

Fig. 3 is a perspective view of my control device.

Fig. 4 is a horizontal sectional view therethrough taken along the line 4—4 of Fig. 3.

Fig. 5 is a vertical sectional view therethrough taken along the line 5—5 of Fig. 4.

Fig. 6 is a perspective view of my improved rotary cylindrical plug or valve.

Fig. 7 is a sectional view therethrough taken along the line 7—7 of Fig. 6.

In the drawings, wherein like characters of reference generally indicate like parts throughout, 10 generally indicates a control cock constructed in accordance with my invention, provided with a suitable type of means for permitting a flow of sufficient gas therethrough to provide a pilot light for the burner. As stated hitherto, my improved control cock is preferably adapted for use for gaseous fuel burners 12 burning a mixture of two gases, one of which is inflammable having the flexible pipes 14 and 16 respectively connecting the respective sources of supply of said gases to the burner 12, in the embodiment shown, the inflammable gas being connected to the burner 12 through the pipe 16 and the non-inflammable gas being connected to the burner through the pipe 14. In the embodiment shown, I have shown a standard type of blow-pipe burner of a type commonly used in soldering small articles, such as, jewelry articles, which burner 12 may comprise the parallel pipes 18 and 20 connectable respectively to the pipes 14 and 16 for the non-inflammable and inflammable gases respectively, joined together by the arm 22 and a mixing pipe 24 projecting obliquely downwardly at the outer end thereof with the non-inflammable gas discharging into the upper end 26 thereof through the pipe 18 and the inflammable gas discharging part way down the length thereof through a hole 28 therein opposite the end of the pipe 28 for the inflammable gas and with the lower end 30 thereof providing a burning tip for the gases mixed in the mixing chamber 32 formed between the hole 28 and tip 30.

In the embodiment shown, the inflammable gas comprises any suitable type of fuel gas, such as, coal gas, water gas, natural gas, acetylene, Philgas, etc., which is connected through the pipe 34 to a point adjacent the work bench 36 and has a pet cock 38 therein with a stub 40 for connecting the end of the flexible pipe 16 thereto. A similar pipe 42 is connected to the source of compressed air, oxygen or other supporter of combustion or other gas used and has a similar pet cock 44 therein, also having a stub 46 therein for connecting the end of the flexible pipe 14 thereto. Employing my improved invention, the pipes 14 and 16 are split into sections so that my invention may be interposed therein.

Broadly, my invention includes a valve casing 48 having a cylindrical bore 50, sets of spaced pipes 52 and 54 and 56 and 58, projecting forwardly and rearwardly from said casing 50 adapted to be interposed in said flexible pipes 14 and 16. I also provide means 60 to mount said cock 10 horizontally or vertically or at any desired angle on the work bench 36. I provide a cylindrical plug 62 rotatably contained within the cylindrical bore 50 of the valve casing 48 having a gas inlet hole 64 therethrough in line when in open position with one set of aligned gas pipes 52 and 56 for the respective sections of the line 14 for the non-inflammable gas and an inlet hole 66 extending therethrough in line with the other set of gas pipes 54 and 58 interposed in the respective sections of the line 16 for the inflammable gas.

I provide suitable means 60 to mount the control cock at any desired angle on the work

bench 36 or other support preferably in the horizontal position shown, although it may be mounted vertically or at any desired angle. I also provide suitable means 70 to secure said rotary plug within said casing against axial movement.

A main novel feature of my invention is that I provide a preferably radial handle 72 for turning said plug 62 in one direction, namely, to an open or closed position, which handle 72 in the embodiment shown also provides suitable means 73 for hanging the burner 12 thereon as shown in Fig. 2. The hanging of the burner 12 on the handle 72 urges the inlet holes 64 and 66 out of alignment with their respective sets of pipes 52 and 56 and 54 and 58, although it is obvious that insofar as certain aspects of my invention are concerned that the handle 72 may be operated by hand or by any other suitable type of mechanism, weight, or otherwise.

A further novel feature of my invention resides in the fact that I provide preferably in combination with the handle 72, which may be actuated as stated by the weight of the burner 12, to shut off my improved control cock, of means to automatically return the rotor or rotary cylindrical plug 62 of my invention to an open position, which, in the embodiment shown, becomes operable on removal of the burner 12 from the handle 72. The specific details of this specific means for positively, automatically moving the rotor to an open or closed position will be described later.

As stated hitherto, my invention is particularly adapted for use in supplying two types of gases to a mixing burner and for this purpose the valve casing 48 is provided with the pipe 54 projecting forwardly therefrom and the pipe 58 projecting rearwardly therefrom, preferably diametrically opposite the pipe 54 and the cylindrical plug 62 is provided with the inlet hole 66 adapted to be brought in and out of alignment with the said inflammable fluid supply pipes 54 and 58 connected to ends of the flexible sections of the pipe 16 which is broken for this purpose to supply the inflammable gas to the burner 12. In a similar manner, the casing 48 is provided with the pipe 52 projecting forwardly therefrom and the pipe 56 projecting rearwardly therefrom preferably diametrically thereof and the cylindrical plug 62 is provided with the preferably diametric inlet hole 64 to provide a conduit through my control device 10 for the non-inflammable gas adapted to be connected to the ends of the flexible sections of the pipe 14 for this purpose. In most instances it is desired to maintain a reduced pilot flame 77 when the cylindrical plug 62 is rotated to a closed position by depression of the handle 72 due to hanging the burner 12 thereon as shown in Fig. 2 and for this purpose it is necessary to by-pass or bleed a small amount of inflammable gas through my improved device when in closed position. I have shown in the drawings two particular types of means for providing sufficient gas for the pilot flame 77. As shown more particularly in Figs. 1, 5 and 7, said by-pass may comprise the by-pass pilot groove 74 extending rearwardly a distance along the periphery thereof at the upper end of said inlet hole 66 and a by-pass pilot peripheral groove 76 extending forwardly therefrom at the lower end of said hole 66 so that when said plug 62 is rotated to a closed position, enough gas will escape through the hollow pipe 58 through the groove 74 to pass through the hole 66 in the plug, the

groove 76 and out through the pipe 54 to provide sufficient inflammable gas to maintain the pilot flame 77.

Alternatively, I may employ a slightly different construction which I have found more desirable for larger units and which comprises an adjusting screw 78 insertable obliquely into a segmental slot 80 cut in the wall of the valve casing 48 adjacent the outer end thereof through which the radial handle 72 may project to limit the turning movement of the plug 62 from a closed to an open position, the plug being in the open position as shown in Fig. 1 when the handle 72 is raised towards a vertical position and the plug 62 being in closed position as shown in Fig. 2 when the handle 72 is moved within the slot 80 away from a vertical position. It is obvious that the adjustment of the adjusting screw 78 may limit the length of the segmental opening 80 for said handle 72 so that the amount that the hole 66 comes out of alignment with the pipe ends 58 and 54 may be adjustably limited to vary the amount of inflammable gas passed through the flexible pipe 16 to the burner.

As stated hitherto, it is necessary to keep the pilot flame 77 burning, or if no pilot flame 77 be used, to provide sufficient inflammable gas at the tip 30 for the lighting thereof and for this purpose, it is highly desirable that the inflammable gas be passed through to the tip 30 faster than the non inflammable gas and my invention further relates to the specific means I preferably employ to increase the speed of the inflammable gas. For this purpose, I construct the inlet hole 66 of a so-called Venturi shape, namely, with the conical portion 82 converging towards the cylinder axis and the conical portion 84 diverging away from the cylinder axis, although, if desired, the point or throat of the smallest diameter need not pass through the cylinder axis. In order to increase the flow of inflammable gas therethrough, the outer ends of the converging and diverging cones 82 and 84 are of larger diameters than the diameters of the pipes 54 and 58, so that as they approach the pipes 54 and 58 they will receive gas therefrom sooner than the non inflammable gas is passed through the smaller true cylindrical hole 64. This is a main feature of my invention, namely, that the holes in the ends of the plug hole 66 are larger than their pipe holes, so that the inflammable gas will flow faster therethrough than the non-inflammable gas will flow through the hole 64 which has pipe holes of the same size as said hole 64. Inasmuch as both gases are under pressure, this insures that the pipe 20 and mixing chamber 32 will be filled with inflammable gas before the non inflammable gas has a chance to reach the chamber 32 through the pipes 14 and 52, inlet hole 64, pipes 56 and 14, burner pipe 18 and oblique pipe 24.

In the embodiment shown, the various parts heretofore referred to are specifically constructed as follows:

As means 60 for mounting my improved control device or cock on the work bench 36 or other support, I provide the valve casing 48, with the internally threaded tubular socket 86 projecting downwardly therefrom and I provide the supporting rod 60 having the screw threaded lower end 88 adjustably insertable in the top of the work bench 36 vertically as shown or at any desired angle if desired and a threaded upper end 90 threadedly contained within said threaded socket 86 to mount said valve casing 48 as shown. 75

horizontally across said flexible pipes or with the cut off ends thereof inserted on the respective casing pipes 52, 54, 56 and 58.

I provide the casing 48 with the closed inner end 92 and I preferably construct the means 70 to retain the plug 62 against axial movement within the casing bore 60 as follows: I provide the circumferential retaining groove 93 in said plug immediately above the end of the hollow socket 86 and I provide the retaining screw 94 having a head 96 externally threaded as at 98 threadedly inserted in said socket 86 above the upper end 90 of the rod 60 having an aligning lug 100 projecting vertically upwardly within the circumferential groove 93 in said valve plug 62 to retain said valve plug 62 in position against axial movement within said valve casing 48.

To provide means to limit the movement of the turning handle 72, as stated, I provide a cut away segment 80 in the outer edge of the valve casing 48 extending the minimum desired turning distance downwardly and forwardly from the top thereof as explained and I provide the fin 102 projecting forwardly from said casing having a screw hole 104 projecting obliquely rearwardly from the bottom of said fin 102 within said segmental cut away portion 80 and the adjusting screw 78 has a shank projecting through said hole 104 within said segmental portion and a head 106 adjustable from underneath said fin 102 to adjustably vary the length thereof to vary the amount of pilot gas by-passed through said inflammable gas line 16 as previously explained.

As stated hitherto, I believe I am the first to provide means of the type about to be described to automatically move the rotary plug 64 of the valve to an open or closed position, in the embodiment shown specifically for moving the plug to an open position although it is obvious that if it be desired to automatically move the plug to a closed position that the improved structure about to be described may be attached to the control device for this purpose. For this purpose, therefore, in the embodiment shown I provide a turning socket 108 projecting downwardly from adjacent the front of the inner end of the valve casing 48 so that the open end 110 thereof discharges upwardly into the hollow interior of the valve casing inside of the front wall of said valve casing 48 in front of the axis of its cylindrical portion. The inner end of the plug 62 is provided with a partially cylindrical cut away portion 112 to provide a partially cylindrical open chamber 114 having a flat upper wall 116 pivotable in the upper portion of said casing. A turning pin 118 projects from the upper end of said turning socket 110 and abuts the front edge of the wall 116 of the cut away portion on the inner end of the plug. A detachable plug or set screw 120 is provided for the lower end of said turning socket and a coil spring 122 or other spring means is interposed between the lower end of the turning pin 118 and plug 120 to urge said turning pin 118 upwardly against the outer edge of said wall 116 to rotate said valve plug 62 to an open position bringing said inlet holes 64 and 66 into alignment with their respective pipes.

I believe I am the first, however, to provide a spring actuated turning pin functioning against a flat surface of a segmental cut away portion of a rotary cylindrical valve 62 to turn it in either direction, either from a closed to an open position, as shown, or from an open to a closed position.

The inner end of the mounting wire 72 is in-

serted within the radial hole 124 in the outer end of the plug so that it may abut the ends of the cut away segmental portion 80, the upper end when in open position and the lower end or end of the adjusting screw 78 when employed in closed position. As shown, I may, if desired, provide an axial hole 126 in the outer end of the plug 62 discharging within said radial hole 124 to receive a retaining screw 128 therein. The mounting wire or handle 72 may be bent in any desired shape for holding the burner 12 thereon, in the embodiment shown extending substantially radially outwardly and having its outer end bent in the form of a hook 73 so that the weight of the burner 12 when hung on the hook 73 may depress said handle from a vertical position shown in Fig. 1 to the lowered position shown in Fig. 2. It is obvious, however, that if my improved device be mounted vertically that the wire 72 may be bent to permit its lowering thereof to bring my control unit to a closed position when the burner 12 is mounted thereon.

In use, the pet cocks 38 and 44 from both gas supply lines 34 and 42 are opened the desired amounts after the burner 12 is removed from the hook handle 73 so that when lighted the flame 19 will be of the desired shape and consistency. The user then uses the burner for soldering or other purposes as long as he desires, but when he is through, he hangs the burner 12 on the hook 73 so that the weight of the burner 12 causes the handle 72 to drop to the position shown in Fig. 2 shutting off the control device to permit a small volume of inflammable gas only to by-pass therethrough sufficient to provide the pilot flame 17 only, the adjustment of the pet cocks 38 and 44 remaining the same. When it is desired to use the burner again it is removed from the hook 73, the turning pin 118 will automatically function to turn the valve 62 to the open position shown in Fig. 1, the proper amount of inflammable gas will by-pass through the pipe 16 to maintain the flames 17 and 19 lighted prior to any passage of the non inflammable gas through the pipe 14 and the device may then be continued to be used while maintaining the same settings on the pet cocks 38 and 44 any desired number of times. It is obvious that, inasmuch as the gas is automatically shut off when not needed and turned on when needed, substantial savings in the amount of gas employed are effected; that time formerly lost in lighting, relighting and readjusting is saved; that the fire hazard is substantially reduced and the other advantages set forth above are achieved.

If desired, my improved control cock may be mounted on the burner 12 so that the pipes 54 and 56 become extensions of the pipes 14 and 18 thereof and, if desired, the turning handle 72 may be moved by a manually actuated movable control member on the burner itself.

It is understood that my invention is not limited to the specific embodiment shown and that various deviations thereof may be made without departing from the spirit and scope of the appended claims.

What I claim is:

1. A control cock for a gaseous fuel burner burning a mixture of two gases, one of which is inflammable, having flexible pipes adapted to supply said gases to the burner, comprising a valve casing having a cylindrical bore, spaced pipes for each gas projecting forwardly and rearwardly from said casing adapted to be interposed in said flexible pipes and a turning socket pro-

jecting downwardly from adjacent the front edge of the inner end of said casing so that the open end thereof discharges upwardly into the hollow interior of said casing inside of the front wall thereof and in front of the axis thereof, a cylindrical plug rotatably contained within said cylindrical valve casing having a gas inlet hole extending therethrough in line when in open position with one set of gas pipes for the non inflammable gas and a gas inlet hole extending therethrough in line with the other set of gas pipes for the inflammable gas, and a partially cylindrical cut away portion at the inner end thereof providing a partially cylindrical chamber having a flat upper wall pivotable in the upper portion of said casing, a turning pin projecting from the upper end of said turning socket and abutting the front edge of the wall of the cut away portion in the inner end of said plug, a detachable plug for the lower end of said turning socket and a coil spring interposed between the lower end of said turning pin and plug to urge said turning pin upwardly against said wall to rotate said valve plug to move said inlet valves to an open position, means to secure said rotary plug within said valve casing against axial movement and a hanger handle mounted on said rotary plug for mounting a burner thereon movable when the burner is mounted thereon to urge the inlet plug holes out of alignment with said pipes.

2. A control cock for a gaseous fuel burner burning a mixture of two gases, one of which is inflammable, having flexible pipes adapted to supply said gases to the burner comprising a valve casing having a cylindrical bore, spaced pipes for each gas projecting forwardly and rearwardly from said casing adapted to be interposed in said flexible pipes, having a cut away segment in the outer edge thereof extending downwardly and forwardly a maximum turning distance from the top thereof, a cylindrical plug rotatably contained within said cylindrical valve casing having a gas inlet hole extending therethrough in line when in open position with the one set of gas pipes for the non inflammable gas and a gas inlet hole extending therethrough in line with the other set of gas pipes for the inflammable gas and an outer end having a radial hole therein within the cut away portion of the valve casing extending substantially vertically when said valve plug is moved to an open position and pivotable to a forward position in the lower edge of said segmental cut away portion, means to secure said rotary plug within said casing against axial movement and a mounting wire projecting outwardly and forwardly from the radial hole in the outer end of said plug having a loop in the outer end thereof for hanging the burner thereon, whereby the weight of the burner may move said plug to urge the inlet plug holes out of alignment with said pipes and means to automatically return the plug to move said inlet holes to an open position operable on removal of said burner from said hanger.

3. A control cock for a gaseous fuel burner burning a mixture of two gases, one of which is inflammable, having flexible pipes adapted to supply the gases to the burner comprising a valve casing having a cylindrical bore, spaced pipes for each gas projecting forwardly and rearwardly from said casing adapted to be interposed in said flexible pipes and an internally threaded tubular mounting socket projecting downwardly, a cylindrical plug rotatably contained within said cylindrical valve casing hav-

ing a gas inlet hole extending therethrough in line when in open position with one set of gas pipes for the non inflammable gas and a gas inlet hole extending therethrough in line with the other set of gas pipes for the non inflammable gas and a circumferential retaining groove therein opposite said mounting socket, a retaining screw having a head threadedly insertable in said socket and an aligning lug projecting vertically within said circumferential groove in said valve plug to retain it in position against axial movement within said valve casing, a supporting rod having a wood screw threaded lower end adjustably insertable within a work bench and a threaded upper end screwed in said socket below said retaining screw to mount said valve casing horizontally across said flexible pipes with the cut off ends thereof inserted within their respective casing pipes, a hanger handle mounted on said plug for mounting the burner therein movable when the burner is hung thereon to urge the inlet holes out of alignment with said pipes and means to automatically return the plug to move said inlet holes to an open position operable on removal of said burner from said hanger.

4. A control cock for a gaseous fuel burner having a flexible pipe adapted to supply gas to the burner, comprising a valve casing having a cylindrical bore, pipes for said gas projecting forwardly and rearwardly from said casing adapted to be interposed in said flexible pipe and a turning socket projecting downwardly from adjacent the front edge of the inner end of said casing so that the open end thereof discharges upwardly into the hollow interior of said casing inside of the front wall thereof and in front of the axis thereof, a cylindrical plug rotatably contained within said cylindrical valve casing having a gas inlet hole extending therethrough in line when in open position with said gas pipes and a partially cylindrical cut away portion at the inner end thereof providing a partially cylindrical chamber having a flat upper wall pivotable in the upper portion of said casing, a turning pin projecting from the upper end of said turning socket and abutting the front edge of the wall of the cut away portion in the inner end of said plug, a detachable plug for the lower end of said turning socket and a coil spring interposed between the lower end of said turning pin and plug to urge said turning pin upwardly against said wall to rotate said valve plug to move said inlet valve to an open position, means to secure said rotary plug within said valve casing against axial movement and a hanger mounted on said rotary plug for mounting a burner thereon movable when the burner is mounted thereon to urge the inlet plug hole out of alignment with said pipes.

5. A control cock for a gaseous fuel burner having a flexible pipe adapted to supply gas to the burner comprising a valve casing having a cylindrical bore, pipes for said gas projecting forwardly and rearwardly from said casing adapted to be interposed in said flexible pipes, having a cut away segment in the outer edge thereof extending downwardly and forwardly a maximum turning distance from the top thereof, a cylind-

rical plug rotatably contained within said cylindrical valve casing having a gas inlet hole extending therethrough in line when in open position with said gas pipes and an outer end having a radial hole therein within the cut away portion of the valve casing extending substantially vertically when said valve plug is moved to an open position and pivotable to a forward position in the lower edge of said segmental cut away portion, means to secure said rotary plug within said casing against axial movement and a mounting wire projecting outwardly and forwardly from the radial hole in the outer end of said plug having a loop in the outer end thereof for hanging the burner thereon whereby the weight of the burner may move said plug to urge the inlet plug hole out of alignment with said pipes and means to automatically return the plug to move said inlet holes to an open position operable on removal of said burner from said hanger.

6. A control cock for a gaseous fuel burner having a flexible pipe adapted to supply gas to the burner comprising a valve casing having a cylindrical bore, pipes for the gas projecting forwardly and rearwardly from said casing adapted to be interposed in said flexible pipe and an internally threaded tubular mounting socket projecting downwardly, a cylindrical plug rotatably contained within said cylindrical valve casing having a fluid inlet hole extending therethrough in line when in open position with said gas pipes and a circumferential retaining groove therein opposite said mounting socket, a retaining screw having a head threadedly insertable in said socket and an aligning lug projecting vertically within said circumferential groove in said valve plug to retain it in position against said axial movement within said valve casing, a supporting rod having a wood screw threaded lower end adjustably insertable within a work bench and a threaded upper end screwed in said socket below said retaining screw to mount said valve casing horizontally across said flexible pipe with the cut off ends thereof inserted within their respective casing pipes, a handle mounted on said plug for mounting the burner therein movable when the burner is hung thereon to urge the inlet hole out of alignment with said pipes and means to automatically return the plug to move said inlet hole to an open position operable on removal of said burner from said hanger.
